UNITED STATES PATENT OFFICE.

LOUIS LACOIN, OF PARIS, FRANCE.

AUTOMOBILE.

SPECIFICATION forming part of Letters Patent No. 763,494, dated June 28, 1904.

Application filed December 26, 1903. Serial No. 186,723. (No model.)

To all whom it may concern:

Be it known that I, LOUIS LACOIN, a citizen of the French Republic, residing in Paris, France, have invented certain new and useful Improvements in or Connected with Automobiles and the Like, (for which I have obtained a patent in France, No. 328,448, bearing date January 13, 1903, and in Great Britain, No. 1,854, bearing date January 26, 1903,) of which the following is a specification.

The frame which forms the object of the present invention is intended to enable a series of vehicles varying in form and dimensions to be made up in an economic manner and at the same time to increase the facility and regularity of the use of these vehicles by rendering possible and practical the attachment of the valuable part of the carriage-framework mounted on two of the wheels to the remainder of the vehicle mounted on the two other wheels and which part comprises the mechanism or the source of power, which is fragile and costly and requires frequent repairs. For this object the frame is divided into two parts, each receiving one of the groups of mechanism or parts hereinbefore specified. One of these parts is joined by means of shafts to a part above the axle of the other section in order to give, so to speak, a direct support to the half-frame of which they form part, the stability of the other part and the solidity of the attachment being assured by a number of bolts, nuts, keys, or other suitable device appropriate for each case, as may be seen in the two examples hereinbefore explained.

In order that the object of this invention may be fully understood, it will now be described as an example with reference to the accompanying drawings, in which—

Figure 1 is a sectional elevation of the rear part of this improved frame made of sheet metal bent round; Fig. 2, a sectional elevation of the fore part of same; Fig. 3, a plan view of half of the rear part, and Fig. 4 a similar view of the front portion of the same frame. Fig. 5 is an elevation, and Fig. 6 a plan view, of a tubular frame arranged under the same conditions. Figs. 7 and 8 are ele-

vations of the two parts, not connected together, of the said tubular frame, showing the projecting shafts, which are secured to the one of these two parts.

In the example of the frame shown in the drawings the fore part, Figs. 2 and 4, is composed of a framework of sheet metal bent round and formed by two longitudinal bars 1 and three cross-bars 2 3 4. These longitudinal bars 1 are connected to the wheels by means of springs 5 and an axle 6 in the ordinary manner and also support the motor and the driving-gear by means of suitable attachments, which are not here shown.

The rear part (shown in Figs. 1 and 3) is also formed of a framework of bent sheet metal formed by means of two longitudinal bars 7, a little wider apart than the bars 1, and three cross-pieces 8 9 10 of the fore part, the longitudinal bars 7 being continued by means of projecting shafts 11. As was the case with the fore part, the springs 12, axle 13, and wheels are connected to the framework in the ordinary manner.

The attachment of the parts is insured:

First. By two supports 14 or brackets and two gudgeons 15, attached on each side of the front frame almost above the axle, Figs. 2 and 4, and by means of two eyelets 16 in each of the shafts 11, which shafts form parts of the rear frame. A nut and bolt 17 completes the attachment at these two points.

Second. By two plates 18, riveted on the longitudinal bars 1 of the fore part and the cross-bars 3 and 4 of the same, and by bolts or bars 19, fixed to the same cross-bars 3 and 4 and adapted to penetrate into two corresponding apertures 20, formed in the front cross-piece 10 of the rear frame, while the plates 18 rest on the projecting shafts 11.

In order to connect the two parts one with another, it is sufficient to keep the rear part of the fore-carriage raised, while the two shafts are slipped under the plates 18 until the gudgeons 15 have been fitted in the eyelets 16 on the projecting shafts. The plates 18 are then allowed to rest on the shafts, the bars or bolts 19 are secured, and the nuts of the gudgeons 15 are tightened. The attachment thus

constituted is rigid and a frame is obtained which entirely resembles other frames. The front part replaces the habitual false frames. The motor, the gearing, the speed-changing gear, the water and spirit reservoirs, the carburetor, the radiator, the lighting device, the steering-gear, with its handles, levers, and pedals, &c., are placed there, and finally the conductor's seat is also placed there. The rear part, which may be more or less elongated, according to the length of the framework, permanently carries the framework, the gearings connected with the rear axle having a multiplying-gear suitable for each car frame, so that with the same motor mechanism there may be obtained different speeds, according as an omnibus, for instance, or a light vehicle is attached thereto.

Tubular framework.—The tubular framework shown in Figs. 5 and 6 is formed of tubes 21, 22, 23, 24, 25, and 26 for the front part and of tubes 27, 28, 29, 30, and 31 for the rear part.

The shafts are formed of two tubes 21, 22, 23, 24, brazed onto the cross-pieces 32 and 33 and simply fitting into the two longitudinal bars 21, 22, 23, 24 of the front part. The attachment is completed by two large grip-screws or head-nuts 34, only one of which is shown in elevation, which firmly secure the two parts 22 to 32 and 24 to 33. In plan view they are concealed.

In case the cross-bars 26 and 29 of the fore and back parts are in the same plane a right and left threaded screw 35, Fig. 6, or similar device will suffice to hold the same together between the bars 26 and 29 instead of the two screws or nuts 34. This form of frame is constructed for smaller weights than the foregoing; but the mechanisms are arranged in the same manner.

Whatever may be the form adopted the judicious use of this frame produces the following advantages: For the builder it is only necessary to make one type of mechanism and framework, the rear part to which the modifications alone apply, coming almost entirely under what is called "coach-building." For the purchaser it enables him to have only a single motor and yet several very different vehicles, such as a victoria for good weather, a closed carriage for the winter, a small omnibus, a landau, a dog-cart, or a goods-wagon, all the said vehicles having suitable speeds. For carriage purposes it is possible to have more vehicles than motors, some of the vehicles being loaded and others discharged, while another vehicle is performing the journey by means of the single motor, cost of depreciation and capital employed being thus reduced to a minimum, or, vice versa, for an omnibus business it is possible to have a change of motors, one being ready to replace any one of the others, and thus insure a regularity of the

service without requiring to incur the expense 65 of an entire omnibus.

Another advantage of the system is that at any given moment the rear carriage may be dispensed with and the motor employed, as is done with a portable engine, for operating any 70 suitable engine, such as a pump, beater, or dynamo for lighting purposes or the like.

This framework may be employed for all kinds of auto-cars whether operated by steam, petroleum, or electricity. In the latter case 75 it may be of advantage to reverse the framework and place the shafts on the fore carriage, the accumulators being, for instance, carried on the rear carriage located between the shafts. The motor-wheels and the steering-wheels 80 may also be distributed in any suitable manner on the two axles. A similar pair may also be both motor and steering wheels. The forms, dimensions, proportions, and accessory parts may be varied, and such material 85 as I may deem suitable may be employed in their construction without departing from the scope of the invention.

Having now particularly described and ascertained the nature of my said invention and 90 in what manner the same is to be performed, I declare that what I claim is—

1. A stiff framework for automobiles; the said framework being adapted to be easily dismountable and including for this purpose 95 two parts which are respectively provided with one axletree and which support respectively the motor parts and the carriage-body; the two said parts being further adapted to be connected together by any suitable means 100 providing an easily-releasable device for attachment, in order to constitute, by uniting of the said two parts, a true stiff framework lying upon two axletrees, substantially as described. 105

2. In a stiff and dismountable framework for automobiles; a first part including a frame provided with an axletree 6; a second part including a frame provided with an axletree 13; two thills 11 fixed on the said second part and adapted to be connected with the first part at the neighborhood of the axletree 6, substantially as described. 110

3. In a stiff and dismountable framework for automobiles; a first part including a frame 115 provided with an axletree 6; a second part including a frame provided with an axletree 13; two thills 11 fixed on the said second part and adapted to be connected with the first part at the neighborhood of the axletree 6; and bearing-surfaces fixed on the said two parts, in order to insure the lying of the framework upon the two axletrees 6 and 13 substantially as described. 120

4. In a stiff and dismountable framework 125 for automobiles; a first frame portion including metallic tubes 21, 22, 23, 24 and provided with an axletree 6; a second frame portion in-

cluding metallic tubes and provided with an axletree 13; two thills 11 fixed on the said second portion, and adapted to engage into the tubes 21 22, 23 24 of the first portion, in order to insure the lying of the second portion simultaneously upon the two axletrees 6 and 13 independently of all securing means; and fastening means to hold the thills 11 in

the tubes 21 22, 23 24, substantially as described.

In witness whereof I have hereunto set my hand in the presence of two witnesses.

LOUIS LACOIN.
